US00D725510S

(12) **United States Design Patent**
Henning

(10) **Patent No.:** **US D725,510 S**
(45) **Date of Patent:** **** Mar. 31, 2015**

(54) **MEASURING INSTRUMENT**

(71) Applicant: **Sony Mobile Communications AB**,
Lund (SE)

(72) Inventor: **Simon Henning**, Lund (SE)

(73) Assignee: **Sony Mobile Communications AB**,
Lund (SE)

(**) Term: **14 Years**

(21) Appl. No.: **29/487,610**

(22) Filed: **Apr. 10, 2014**

(30) **Foreign Application Priority Data**

Nov. 6, 2013 (EM) 002340166

(51) **LOC (10) Cl.** **10-04**

(52) **U.S. Cl.**
USPC **D10/70; D10/78**

(58) **Field of Classification Search**

(57) **CLAIM**

The ornamental design for a measuring instrument, as shown and described.

DESCRIPTION

FIG. 1 is a perspective view of a measuring instrument in a closed position showing my new design.

FIG. 2 is another perspective view thereof.

FIG. 3 is a front view thereof.

FIG. 4 is a left side view thereof.

FIG. 5 is a perspective view of the measuring instrument in an open position;

FIG. 6 is another perspective view thereof; and,

FIG. 7 is a left side view thereof.

The broken lines are for the purpose of illustrating portions of the measuring instrument and form no part of the claimed design.

1 Claim, 7 Drawing Sheets

US D725,510 S
